L. F. CHANEY

AIR CONTROL VALVE

Filed Nov. 12, 1920

UNITED STATES PATENT OFFICE.

LEE F. CHANEY, OF SPRINGFIELD, OHIO, ASSIGNOR TO THE CHANEY MANUFACTURING COMPANY, OF SPRINGFIELD, OHIO, A CORPORATION OF OHIO.

AIR-CONTROL VALVE.

Application filed November 12, 1920. Serial No. 423,656.

To all whom it may concern:

Be it known that I, LEE F. CHANEY, a citizen of the United States, residing at Springfield, in the county of Clarke and

5 State of Ohio, have invented certain new and useful Improvements in Air-Control Valves, of which the following is a specification.

This invention relates to air pressure control valves, and more particularly to an inflation apparatus having provision for the immediate and instantaneous release of back pressure, upon the closing of the supply valve.

10 As is illustrated in the drawings the invention has been shown applied to the blowing of glass articles, in this instance a thermometer bulb, but which is obviously applicable to other purposes, wherein a fluid under pressure is utilized as an operating medium.

15 The object of the invention is to simplify the structure as well as the means and mode of operation of such devices, whereby they 25 will not only be cheapened in construction, but will be more efficient in use, positive in operation, automatic in action, easily controlled and unlikely to get out of repair.

20 A further object of the invention is to provide an apparatus adaptable for the blowing of thermometer bulbs or other analogous operations, which will be compact, efficient and under instant control of the operator at all times.

25 With the above primary and other incidental objects in view as will more fully appear in the specification, the invention consists of the features of construction, the parts and combinations thereof and the mode of operation or their equivalents as hereinafter described and set forth in the claims.

30 Referring to the drawings, wherein is shown the preferred, but obviously not the only form of embodiment of the invention, Fig. 1 is a side elevation of a blast burner and air connection, for heating the article, in this instance a thermometer bulb, to which the fluid pressure is to be applied, together with the fluid pressure conduit and control means. Fig. 2 is a detail sectional view of the fluid pressure control valve, illustrating the finger control. Fig. 3 is a detail sectional view of a modification of the 35 cut-off valve for the fluid under pressure.

Fig. 4 is a top plan view illustrating the relation of the valve plunger and the vent passage. Fig. 5 is a detail sectional view of a modification.

Like parts are indicated by similar characters of reference throughout the several views.

While the present invention is capable of a wide range of application, wherein fluid under pressure is employed, as for instance in blow torches for jewelers, gas or fluid supplying apparatus, and glass blowing purposes, it has been shown in the present instance for illustrative purposes, in conjunction with the manufacture of thermometer 70 tubes, wherein it is utilized for expanding the bulb.

In the commercial manufacture of thermometer tubes, the tube having therein a capillary bore, is heated in a blast torch or burner and one end is closed. Thereafter it is heated and air under pressure is supplied thru the capillary bore sometimes by the operator applying the tube to his lips and blowing therethru, but a more practical method is to utilize air under pressure from a suitable source of mechanical supply. In such instances, the capillary tube is attached to a flexible rubber tube or hose, thru which the air supply is conducted. It has 85 been found that in such operation, it is not sufficient to merely cut off the air supply when the plastic end of the tube has been expanded to the desired degree, but it is necessary to instantly relieve the pressure within 90 the tube. If this pressure is not released, but the supply merely cut off, the internal pressure within the plastic bulb will continue to expand the same, and the result will be variations in the size of different bulbs depending upon the degree of plasticity, at the time the air supply is cut off. To this end the present apparatus embodies means for instantly relieving such back pressure. Two 100 way or release valves of mechanical construction have not been found satisfactory because of the momentary interval between the closing of the supply ducts and the opening of the release ducts, during which time the size of the plastic bulb has changed. The 105 present type of finger control release port is designed to overcome this difficulty.

Referring to the drawings, 1 is a supply conduit for gaseous fuel and 2 a similar conduit for air or other expanding medium 110

under pressure. In the present instance a branch conduit 3 leads from the air supply conduit 2, and projects thru the open end of a lateral conduit 1^a of the supply conduit to a point beyond the upright pipe 1. The lateral conduit 1^a is reversed and carries at its extremity a burner head 4, comprising a sleeve having therein a packing or filling of steel wool, or other porous non-combustible material. The discharge of a jet of air under pressure thru the lateral fuel supply conduit 1^a affords a blast or blow torch effect which produces a concentrated flame of intense heat, which is projected from the extremity of the burner head 4. The thermometer tube to be treated is attached to a length of flexible tubing or hose 6, with which the fluid pressure supply conduit will communicate thru a lateral extension 2^a, which carries a control valve mechanism 7, from which the flexible tube 6 leads laterally. This control valve may be of any suitable design or construction. In the drawing it has been shown as assembled from standard pipe fittings. Secured to the lateral extension 2^a, of the fluid pressure supply line, is an ordinary elbow 8, carrying a tapered nipple 9, having a reduced orifice 10, controlled by a ball valve 11. The ball valve 11 will be ordinarily forced to its seat in the contracted end of the nipple 9 by the pressure of the fluid within the supply conduit. The ball is held in proximity to its tapered seat adjacent to the orifice 10, and prevented from falling within the conduit in the event the air supply is decreased by means of a transverse pin 12, extending thru the nipple 9. However in lieu of this construction, the ball valve 11 may be actuated toward its seat by means of a helical spring as shown in the detail view Fig. 3. This spring 13 resting upon the transverse pin 12 normally tends to hold the ball valve in closed position in relation with the orifice 10 of the nipple independent of variations of the fluid supply pressure. Screw threaded upon the upturned nipple 9 is an ordinary T connection 14 to the lateral outlet of which the flexible hose 6 is connected. Screw threaded in the top or uppermost outlet of the T connection 14 is a reducer or bushing 15, which forms a guide for a longitudinally movable plunger or stem 16. The upper portion of this stem 16, which extends thru the bushing or guide 15, is preferably flattened or of polygonal form to afford intermediate the plunger and the inner face of the bushing 15, ample vent space 17 as particularly shown in detail view Fig. 4. The lower end of the plunger or stem 16 is of reduced diameter and projects thru the orifice 10 in the end of the nipple 9 where it engages the ball valve 11. The plunger stem 16 is of sufficient length to project slightly above the level of the guide or bushing 15, when

the ball valve is seated. The plunger or stem is thus normally supported upon the ball valve 11, and is free for longitudinal movement or depression against the tension of the fluid under pressure beneath the ball valve, and in the construction shown in Fig. 3, against the tension of the retracting spring 13.

In operation the thermometer tube 5 is inserted in the end of the flexible hose 6, and held within the range of the flame ejected from the burner 4 until the extremity of the glass tube is sufficiently fused to become plastic. The operator then places a finger upon the protruding extremity of the plunger stem 16, depressing the stem and opening the port 10 by forcing the ball valve 11 downwardly. This depressing movement of the operator's finger upon the plunger 16 also serves to close by means of the finger, the relief space or port 17 about the plunger, and within the bushing or guide 15. So long as the operator holds the plunger depressed, his finger will effectively close the outlet port 17, and the air under pressure or other operating fluid discharged thru the port 10 into the chamber of the T connection 14, passes thence thru the flexible tubing or hose 6 into the thermometer tube 5 and serves to expand the fused or plastic end of the tube to form the bulb 5'. It is customary to scale the size of the bulb by inserting it within a gage during the blowing operation. The operator may control the expansion of the plastic bulb by admitting intermittent small charges of fluid under pressure by momentarily depressing the valve plunger 16, or he may admit an ample initial charge sufficient to expand the bulb and then immediately lift the finger from the control valve. The release of the valve plunger 16 by removal of the operator's finger at the same time opens the relief port 17, about such plunger and the back pressure within the expanded bulb is relieved instantly, synchronously with the closing of the valve 11. By this means the shutting off of the air supply and release of back pressure is effected in unison, and consequently there is no intervening interval during which the plastic bulb may continue to swell under the influence of the entrapped air pressure. Instead of employing a separate valve construction for the relief of back pressure, the operator's finger performs the function of retaining the pressure as long as pressure is desired and of relieving such pressure by the removal of the finger from the apparatus.

It has been found in practice that the present construction enables the production of thermometer bulbs commercially in large quantities with great rapidity and with extreme accuracy. The result achieved in the manufacture of thermometer tubes are also

possible in the manufacture of other articles wherein an inflation operation or the discharge of fluid under pressure is to be instantly arrested or the instant release of back

5 pressure to be effected, or in which these results are to be attained simultaneously.

In lieu of using the operator's finger as a closure for the vent orifice there has been shown in Fig. 5, a modification, wherein a

10 spring, actuated valve stem 18 carries at its lower end a valve head 19, controlling the supply orifice, and at its upper end a valve head 20, controlling the vent orifice. By depressing the valve stem 18 by means of a finger 21, the supply valve is opened and the vent valve closed. The supply valve is automatically closed and the vent simultaneously opened under the influence of the spring 22 upon removal of finger pressure.

15 20 From the above description it will be apparent that there is thus provided a device of the character described, possessing the particular features of advantage before enumerated as desirable, but which obviously 25 is susceptible of modification in its form, proportions, detail construction and arrangement of parts without departing from the principle involved or sacrificing any of its advantages.

30 35 While in order to comply with the statute the invention has been described in language more or less specific as to structural features, it is to be understood that the invention is not limited to the specific details shown, but that the means and construction herein disclosed comprise but one of several modes of putting the invention into effect, and the invention is therefore claimed in any of its forms or modifications within the legitimate 40 and valid scope of the appended claims.

Having thus described my invention, I claim:

1. In a construction of the character described, a chamber having a vent orifice, a 45 control valve admitting fluid under pressure to said chamber, and a depressible valve operating plunger extending thru the vent orifice whereby the operator's finger in depressing the plunger will close the vent orifice and the removal of the operator's finger to release the air pressure will open the vent orifice.

2. A pressure chamber, having a vent orifice to be closed by the finger of the operator, 55 a control valve admitting pressure to said

chamber, and finger operated means for opening said valve manipulated by the application of the operator's finger to the vent orifice.

3. In a construction of the character described, a pressure chamber having a normally open vent orifice, a control valve admitting fluid under pressure to said chamber, and means whereby the application of the operator's finger to close the vent port 60 65 will simultaneously open said valve and vice versa.

4. In a construction of the character described, a pressure chamber having a vent orifice normally open to atmosphere and 70 adapted to be closed by the application of the finger of the operator, a control valve admitting fluid under pressure to said chamber, and valve operating means located in such proximity to the vent orifice as to be 75 operatively engaged by the finger of the operator in stopping said vent.

5. In a construction of the character described, a pressure chamber having therein an orifice normally open to atmosphere, a 80 control valve admitting fluid under pressure to the chamber, a valve operating stem extending within the orifice, said orifice and the stem being of different shapes whereby an escape passage will be afforded for the 85 fluid under pressure thru the orifice beside the stem, said stem being adapted to be operated and the escape passage closed by the application of the operator's finger.

6. In a device for blowing thermometer 90 bulbs and like operations, a supply of fluid under pressure, a control valve therefor and a finger stopped relief port for back pressure.

7. In a device for blowing thermometer 95 bulbs and like operations, a supply conduit for fluid under pressure, a depressible control valve therefor, said conduit having therein a vent port normally open to atmosphere intermediate the valve and the point 100 of operation, said vent port being closable upon the depression of said valve.

In testimony whereof, I have hereunto set my hand this 5th day of November, A. D. 1920.

LEE F. CHANEY.
